J. STEIGERWALD

ROPE AND WIRE HOLDER

Filed Aug. 27, 1924

FIG. 2.

FIG. 3.

FIG. 4.

FIG. 5.

Inventor:

JOHN STEIGERWALD,

Monroe C. Miller
Attorney

Patented July 14, 1925.

1,546,046

UNITED STATES PATENT OFFICE.

JOHN STEIGERWALD, OF FORT WAYNE, INDIANA.

ROPE AND WIRE HOLDER.

Application filed August 27, 1924. Serial No. 734,484.

To all whom it may concern:

Be it known that I, JOHN STEIGERWALD, a citizen of United States, residing at Fort Wayne, in the county of Allen and State of Indiana, have invented certain new and useful Improvements in Rope and Wire Holders, of which the following is a specification, reference being had therein to the accompanying drawing.

10. The present invention relates to holders for ropes, wires, cables and the like, and aims to provide a novel and improved device of that kind to be applied to the doubled portion of the rope, wire or other 15 flexible element near the loop thereof, for holding the loop closed and preventing the portions of the flexible element from sliding relatively to one another.

It is also an object of the invention to 20 provide such a device constructed from a single piece which can be readily cast from suitable metal or otherwise inexpensively manufactured without requiring machine work or other expensive manufacturing 25 process.

With the foregoing and other objects in view, which will be apparent as the invention is more fully understood, the invention resides in the formation of the member constituting the holder in a novel and improved manner to engage and hold the flexible element in an effective manner, it being understood that changes can be made within the scope of what is hereinafter claimed, without departing from the spirit of the invention.

The invention is illustrated in the accompanying drawing, wherein—

Figure 1 is a side elevation of the holder 40 as in use.

Fig. 2 is a plan view thereof.

Fig. 3 is an opposite plan view showing the holder by itself.

Fig. 4 is a cross section on the line 4—45 1 of Fig. 1.

Fig. 5 is a side elevation showing how the holder is applied to the flexible element, with the holder in its initial position.

The holder comprises a single part or 50 member that may be cast, forged or otherwise formed from aluminum or any other suitable metal. Said member comprises the elongated body or bar 7 having the lug 8 projecting at an angle from one side at 55 one end of said body, and said lug is formed with a notch 9 adjacent to the body 7 at

that side of the lug which faces the opposite end of the body, so that the lug 8 forms a hook. The body 7 is provided with a pin or stud 10 projecting from the same side 60 thereof and located near the end of the body opposite to the lug or hook 8.

Between the lug 8 and stud 10 the body 7 has the outstanding portion 11 projecting from the same side of the body as the lug 65 and stud, and said portion 11 is of tapered or wedge form in plan when looking at either edge of the body 7, as seen in Figs. 2 and 3. The wider end of the portion 11 is located adjacent to but spaced from the lug 70 or hook 8, to provide a laterally opening slot 12 leading to the notch 9, said slot and notch extending transversely across the corresponding side of the body or bar 7. The portion 11 is provided with a wing or flange 75 13 projecting from the outer side thereof in the direction that the corresponding edge of the body or bar 7 faces, and said portion 11 is formed with the longitudinal groove 14 extending from the slot 12. The wing or flange 13 extends from the slot 12 and tapers off at its opposite end between the ends of the portion 11, and said portion 11 has the surface 15 continuing from the corresponding end of the groove 14 and spaced 80 from the stud 10, the groove 14 and surface 15 being disposed obliquely relatively to the side of the body 7, as seen in Figs. 1 and 5. The flange or wing 13 is of wedge-shaped cross section, and the groove 14 is also of 85 wedge-shaped cross section, as seen in Fig. 4.

The device is used for holding or fastening together the portions 20 of a flexible element which have been doubled together, to form the loop 21 which surrounds a member 22. The flexible element may be a rope, cable, or the like, and may be electric conductors or wires looped around an insulator represented by the member 22, and it will be understood that the device can be used for 95 various purposes for which it is suitable.

In applying the holder, reference being had to Fig. 5, the holder is disposed at an angle with the flexible element to extend across said element, and the holder is then 105 moved transversely so as to position the portions 20 of the flexible element in the slot 12, with the body 7 at one side and the wing or flange 13 at the opposite side. Then, the holder is swung away from the object or 110 member 22 in the direction of the arrow in Fig. 5, and this will kink or bend the por-

tions 20 of the flexible element where they extend across the lug or hook 8 and the adjacent end of the portion 11, as seen in Fig. 1. The notch 9 will receive the portions 20, 5 to hold them together, and said portions will also be received by the groove 14 in which they will be wedged together between the converging walls of said groove, as seen in Fig. 4. The wing or flange 13 passes 10 across the flexible element opposite to the body or bar 7. Before the body or bar 7 is swung to final position it is swung transversely to engage the pin or stud 10 across the portions 20 opposite to the portion 11. 15 This is readily done by separating the flexible element and corresponding terminal of the body 7 to enable the stud or pin 10 to be engaged with the flexible element.

As shown in the drawings, the holder is 20 applied to the portion 11 above the flexible element and the stud 10 below said element. Thus, as seen in Fig. 5, the holder is positioned with the lug 8 below and the portion 11 above the flexible element. The holder 25 is then swung toward the right, as seen in Fig. 5, to move the flange or wing 13 down across the side of the flexible element facing the observer, and the right hand end of the body 7 and flexible element are separated 30 so that the stud or pin 10 can be engaged under the flexible element.

The portions 20 of the flexible element are frictionally held together between the flange or wing 13 and body 7, and within 35 the notch 9, thereby preventing said portions 20 from slipping or sliding longitudinally relatively to one another, and the loop 21 is also held closed. The portions 20 are also bent where they extend across the 40 lug 8, the adjacent end of the portion 11 and the stud 10.

Having thus described the invention, what is claimed as new is:—

1. A holder of the character described comprising a member having a lug, a stud 45 and a portion outstanding from one side thereof with said portion between the lug and stud, with a slot between said lug and portion to receive a doubled flexible element, said portion having a substantially longitudinal groove of a width to receive the two portions of the flexible element side by side in contact with the opposite walls of the groove, said walls converging so that said portions of the flexible element wedge between said walls when said element is tightened, and said stud being engageable 50 across the flexible element opposite to said portion.

2. A holder of the character described 60 comprising an elongated body having a lug and a stud outstanding from one side thereof at opposite ends of said body, and having a portion outstanding from said side between said lug and stud, with a slot between 65 said lug and portion to receive a doubled flexible element, said lug having a notch for the engagement of the two portions of said element disposed side by side, said portion having a flange and a longitudinal groove 70 between said flange and body to receive said portions of the flexible element side by side in contact with the opposite walls of said groove, said walls converging so that said portions of the flexible element wedge between 75 said walls when said element is tightened, and said stud being engageable across said flexible element opposite to said portion.

In testimony whereof I hereunto affix my 80 signature.

JOHN STEIGERWALD.
